US00D883237S

(12) **United States Design Patent** (10) Patent No.: **US D883,237 S**
(45) Date of Patent: **** May 5, 2020**

(54) **ELECTRICAL SWITCH**(71) Applicant: **SIMON, S.A.U.**, Barcelona (ES)(72) Inventors: **Salvi Plaja Miro**, Barcelona (ES);
Adria Rique Rebull, Barcelona (ES);
Clara Batiste Mayas, Barcelona (ES);
Marta Portillo Lainez, Barcelona (ES)(73) Assignee: **SIMON, S.A.U.**, Barcelona (ES)(**) Term: **15 Years**(21) Appl. No.: **29/681,123**(22) Filed: **Feb. 22, 2019**
